UNITED STATES PATENT OFFICE

FRANCIS J. STOKES, OF PHILADELPHIA, PENNSYLVANIA

METHOD OF FINISHING YARNS OR FABRICS

Application filed June 22, 1925. Serial No. 38,697.

The principal object of the invention is to effect a material economy in dyeing or bleaching or otherwise finishing yarns and fabrics by the provision of a process which makes it possible to dye or bleach the material in the standard package or form in which it is normally produced in the course of its manufacture, and thereby to save the time and expense which is now necessary for preparing the material for dyeing. As an illustration, yarn in the course of its manufacture is wound on cops, cones, bobbins or tubes on standard winding machines. Heretofore in order to dye the yarn it was necessary to rewind it into skeins on a reel or to initially wind it on special perforated cores to permit the dye to penetrate. It was necessary, after the dyeing process, to rewind the yarn onto cops, tubes, bobbins or cones before it could be further fabricated. The elimination, by the present invention, of these operations entails a saving of from four to eight cents a pound depending upon the size and kind of yarn. In the case of cloth the bolt can be finished or dyed in the piece without unwinding.

Generally stated, the invention consists in exhausting or removing air from the yarn or fabric to be dyed, bleached or otherwise finished by subjecting it in the standard package or form in which it is normally produced in the course of its manufacture to the action of a vacuum, while under the influence of a vacuum immersing or flooding the yarn or fabric with one or more liquid dyes or other finishing agents including water and after it is submerged applying atmospheric or air pressure to the liquid to force it into the material, with or without heat for setting the dye, and flowing off or withdrawing the surplus liquid. As a modification of this method and for optional use, after the withdrawal of the surplus liquid, the textile or material may be subjected to centrifugal action for drying. It is also possible after the withdrawal of the surplus liquid and the starting of the centrifugal, to apply additional liquid, heated or otherwise, to the material while under centrifugal action, either in the atmosphere or in a vacuum, drying the material by further centrifugal action and removing the

finished product for use or for further fabrication.

The invention also comprises the improvements to be presently described and finally claimed.

In the single figure of the accompanying drawing there is illustrated apparatus of one form selected from among other forms that may be used in the practice of the invention in both of its aspects.

In the drawing 1 is a tank shown as fitted with a door 2, a valved vacuum connection 3, an air inlet connection 4, and the basket 5 of a centrifugal machine of which parts are indicated at 6, 7 and 8. The steam jacket 18 is an example of means for heating the contents of the tank 1. 9, 10 and 11 are tanks which may or may not be heated as the character of the dye or finishing agent employed may require. There are valved pipe connections 12, to the interior of the basket 5, and these valved connections 12 are shown as fitted with a valved branch 13 to a water supply and with a valved branch 14 including a pump 15 to the various tanks 9, 10 and 11. There are other valved connections 16 including a pump 17, that extend from the various tanks 9, 10 and 11 to the tank 1.

The invention can be best explained by describing the process of dyeing yarn on cops, bobbins, cones, tubes or spools, i. e. in the standard package or form in which it is normally produced in the course of its manufacture. The yarn on cones, tubes, cops, bobbins or spools is placed in the basket 5 of the centrifugal machine leaving an open space or well in the center in which the spray pipe 12 may be admitted. The tank 1 is then closed and a vacuum produced by means of a vacuum pump through the connection 3. The result is that air is removed from the yarn in order to permit the dye or finishing agent, including water, to penetrate freely. The liquid dye is introduced from the bottom of the tank 1, and while a vacuum is still maintained. By means of the pipe and valve connections 16 the desired dye color can be supplied or pumped into the vacuum chamber 1 from its storage tank 9, 10 or 11. By having a number of storage tanks various dyes or bleach can

be kept on hand. After the yarn is completely submerged air pressure is applied by breaking the vacuum or by means of an air compressor, as at 4, which rapidly forces the 5 dye and distributes it evenly through the yarn. The dye or finishing agent can then be heated if its nature demands it. The surplus dye is then withdrawn by means of suitable pipe connections, as 16, and the yarn 10 either removed or submitted to centrifugal action for drying, or it may be washed by admitting water through the spray pipe 12 and connections supplied for the purpose. It may be that owing to the nature of the dye and in 15 order to obtain a uniform shade of color throughout the yarn, it will be necessary to circulate the dye through the yarn, and this can be accomplished by introducing the dye through the spray pipe 12 after the surplus 20 dye has been first pumped out of the tank 1 after the initial impregnation and while the yarn is still under vacuum. In some cases it may be advisable to circulate the dye through the yarn. The centrifugal action will throw 25 the dye from the spray 12 through the yarn and cause a circulation producing a uniform coloring. In some cases after the dyeing has been accomplished it may be necessary to wash the yarn, and this is done by following 30 the dye with wash water. 95

In some cases the liquid or finishing agent employed in the vacuum and pressure steps may be water, followed, after drawing off the water from the tank 1, by heated dye applied 35 under substantially atmospheric conditions and under centrifugal action and by the spray 12. 100

Where yarn is washed or bleached the process is as above described with the exception 40 that a liquid soap or bleach is substituted for the dye. Where indirect colors are used the application of a mordant, fix and dye is followed out in the usual sequence as now practiced, but applied in the manner above de- 45 scribed. 110

In the foregoing description reference has been made to the practice of the invention in a single tank 1, but of course the steps or some of them of the process can be practiced in 50 separate vessels in which case the material may be lifted out of the vacuum treating tank and transferred to a centrifugal. 115

As used in this specification and claim the term "treating liquor" includes water, dyes, 55 mordants, bleaches, soaps and similar liquids now used in the commercial production of textiles. 120

It will be obvious to those skilled in the art to which the invention relates that modifications may be made in details of procedure and in matters of mere form without departing 60 from the spirit of the invention which is not limited as to such things or otherwise than as the prior art and the appended claim 65 may require. 125

I claim:

The method of finishing yarns or fabrics which consists in removing air from the material by subjecting it in the standard package in which it is normally produced in the course of its manufacture to the action of 70 vacuum, while under the influence of vacuum, flooding the material with a treating liquor, applying air at least at atmospheric pressure to the treating liquor in which the material is submerged, separating the material and the surplus treating liquor, and applying additional treating liquor to the material while 75 under centrifugal action. 130
